RELAY

Robert Vradenburgh, Yonkers, N. Y., assignor to
 Ward Leonard Electric Company, a corporation
 of New York

Application February 6, 1941, Serial No. 377,678

7 Claims. (Cl. 200—87)

This invention relates to relays adapted for use by either alternating or direct current and adapted for the control of one or more circuits for various purposes, such as the control of electric heaters, signals, lights, pumps, compressors and the like. The relay is herein shown and described as of a single pole type, although various features of the invention are adapted for use in multi-pole relays.

One object of the invention is to produce a relay of compact construction occupying small space and comprising a small number of parts which may be produced at low cost and readily assembled and be durable under long continued operation. Another object is to impose pressure on the contacts in both the attracted and unattracted positions of the armature by a single spring. Another object is to permit the use of a compression spring instead of a tension spring and thereby avoid the possibility of the parts becoming free and causing possible damage by accidental contact of the free part or parts. By using a compression spring suitably confined, the spring, even if broken, will always function to exert some pressure. Another object is to impose a wiping contact action on the contacts after their closure so as to be self-cleaning and insure a good electrical contact. Another object is to provide a large area of contact between the movable armature and the fixed part of the magnetic circuit and provide low reluctance in the bearing support when the armature is in the open circuit position and thereby reduce the ratio of open to closed impedance. Another object is to provide a structure which will retain the parts in their proper relative positions at all times and not be subject to displacement by shocks or jars. Other objects and advantages will be understood from the following description and accompanying drawing which illustrate one embodiment of the invention.

Fig. 1 is a front elevation; Fig. 2 is a side view partly in section; Fig. 3 is a side view partly in section showing the parts in an intermediate position; and Fig. 4 is an end view.

The parts are shown mounted on a base 1 of insulating material. The controlling coil 2 is provided with a central core 3 having a shading coil or closed loop 4 at its outer end, one portion of the loop passing through a slot in the outer end of the core. The fixed magnet frame 5 is composed of a strip of iron or steel bent at right-angles to form one portion extending along the base and the other portion extending outwardly. It is fixed to the base by two screws 6 which pass

5 through the base and engage the upwardly extending leg of the magnet frame, the upper screw entering the inner end of the core 3 and serving to hold it firmly against the upward extension of the magnet frame. The terminals of the coil are connected to binding posts 7 which are fixed to the base and are positioned at opposite sides of the coil. They are provided with screws 7a at the top of the posts and with washers 7b with outwardly turned edges broken away at a portion thereof for convenient connection of leads thereto.

10 The movable armature is formed of a strip of iron or steel having a leg 8 extending upwardly and passing over the outer end of the core of the magnet, this leg being bent almost at right-angles to the other leg 8a of the armature which extends inwardly and along the outwardly extending leg of the magnet frame. The armature is pivotally mounted upon the outer end of the magnet frame.

15 The contact finger is also composed of a strip of metal which may be of non-magnetic material or of iron or steel and is in the form of two legs 9 and 9a bent to an angle of almost 90° with reference to each other. The leg 9 extends over and beyond the leg 8 of the movable armature and carries the movable contact 9b at its end. The leg 9a extends inwardly and over the outer 20 surface of the leg 8a of the movable armature. The finger is provided with punched out metal extensions 9c which are bent over to clamp the end of the flexible lead 10 and to hold it in fixed connection therewith. The end of the lead is 25 soldered to the finger at one of the clamps to maintain good electrical connection. The lead 10 is connected to its binding post 11 fixed to the base for convenient connection to an outside lead. The inner end of the contact finger near 30 the base is provided with inwardly bent ears 9d at opposite sides which extend toward the coil and loosely embrace the inner end of the movable armature and a portion of the magnet frame to serve as guides and to assist in maintaining 35 the parts in proper relationship. The upper and outer end of the movable armature is also provided with ears 8b which are bent to extend outwardly and loosely embrace the upper end of the contact finger for the purpose of maintaining 40 these parts in proper relation to each other.

45 A pin 12 is fixed at its inner end, by riveting or otherwise, to the outwardly extending leg of the magnet frame 5 and extends downwardly and freely through a slot 8c in the movable armature and through an opening 9e in the leg

9a of the contact finger. A compression spring 13 surrounds this pin and is seated at its inner end against a cup washer 14 and retained in place at its outer end by a cup washer 14a. The outer end of the pin 12 is grooved to receive a U-shaped retaining element 15 which may readily be slipped into place for retaining the washer 14a in place and for imposing suitable pressure upon the spring. Within the spring is a loosely positioned sleeve 16 which is of slightly less length than the distance between the cup washers 14 and 14a when the armature is in its attracted position, this sleeve serving to prevent undue side-wise movement of the parts about the pin in uses where the relay might be subjected to extreme shocks or jars. Such possible side-wise movement causes one side of the washer 14 to be forced outwardly and engage the inner end of the sleeve and thereby prevents any further pronounced side-wise movement of the upper end of the movable armature and contact finger.

The leg 8a of the armature is provided with a pair of outwardly forced projections 17 which are positioned outwardly with relation to the pin 12 and located one at each side thereof, as shown in Figs. 1 and 2. These serve as pivot points for the contact finger except when the latter is in its fully attracted position. The relay is shown provided with an inner fixed contact 18 and an outer fixed contact 19 adapted to be engaged by the contact of the finger respectively when in its attracted and unattracted positions. The inner fixed contact is supported by a strip of metal 18a which extends side-wise and is then bent to extend towards the base and then again bent at the base to extend under the fixed binding post 18b. The outer fixed contact is supported by a strip of metal 19a which extends side-wise and then bent to extend toward the base and again bent at the base to extend under the fixed binding post 19b. It is obvious that a circuit connected to the binding posts 11 and 18b will be closed when the relay is in its attracted position and that a circuit connected to the binding posts 11 and 19b will be closed when the relay is in its unattracted position. The relay may be connected to secure various circuit controls according to the particular requirements.

Fig. 2 shows the parts in their relative positions when the relay is deenergized, the movable contact then engaging the outer fixed contact. In this position the spring 13, by exerting its pressure against the leg 9a of the contact finger and in turn against the projections 17, holds the armature outwardly; and also by reason of the spring pressure being exerted on the inner portion of the leg 9a of the contact finger at its inner portion with reference to the projections 17, it forces the leg 9 of the contact finger outwardly and thereby forces the movable contact 9b with adequate pressure against the fixed contact 19. When current passes through the coil of the relay equal to or exceeding the pick-up value, the armature 8 will be attracted toward the outer end of the magnet core and will turn about the outer end of the fixed magnet frame 5 as a pivot. In its initial movement the armature moves independently of the contact finger until the inner end of the armature swings downwardly to engage the inner end of the contact finger. It then forces the contact finger to move with the armature and thereby causes the movable contact to engage the fixed contact 18.

as shown by the full line position of the parts in Fig. 3. The continued movement of the armature from this position to the end of the magnet core then causes the inner end of the armature to force the contact finger downwardly and to take a position below the projection 17, as indicated by the dotted lines in Fig. 3. In this latter movement, the movable contact is moved downwardly, giving a wiping contact in this portion of the movement. This, of course, serves to maintain the contacts clean and insures a good electrical contact during long continued use. Although the relay may be mounted in any position, it is usually mounted in a vertical position as shown in the drawing and any arc that may form tends to occur at or near the upper portion of the contact area. Consequently the downward movement of the contact in its wiping action just described, moves the contact away from the arcing region and thereby causes the contacts to engage an area which has been least affected by the arcing. Thus the direction of movement in this wiping contact action is of special advantage when the relay is mounted in a vertical position.

When the coil of the relay is deenergized or its current reduced sufficiently to release the armature, the spring 13 will act to first move leg 9a of the contact finger toward the armature and against the projections 17 and in such action causes the movable contact to wipe against the contact 18 before separating from that contact. The spring then moves both the contact finger and armature about the outer end of the magnet frame, thereby separating the movable contact from the fixed contact 18 and moving it into engagement with the fixed contact 19. During this action the leg 9a of the contact finger engages the inner end of the leg 8a and likewise the projections 17. After engagement with the fixed contact 19, the pressure of the spring against the leg 9a of the contact finger and through it against the projections 17, forces the leg 9a closely against the outwardly extending arm of the magnet frame. This final movement permits the leg 9a of the contact finger to move somewhat towards the projecting arm of the magnet frame and thereby results in a wiping action of the movable contact against the fixed contact 19 after engagement of these contacts. When the armature is again attracted, the reverse action takes place.

It is evident that the relay is of compact construction and made of parts which may be easily and economically manufactured and readily assembled and disassembled. The single spring serves to impose pressure of the movable contact against the fixed contacts in both the attracted and unattracted positions of the relay and thereby avoids the use of a flexible contact carrying arm usually associated with relays having a single spring. In this case the term spring is interpreted as that type constructed with spring wire suitably coiled on a mandrel as distinguished from a flat or leaf spring. The contacts may be silver faced if desired. The wiping action of the contacts render them self-cleaning and insures good contact in both the attracted and unattracted positions of the relay. In case the relay is used for closing a circuit in the attracted position only, the outer fixed contact 19 and its supporting strip may be omitted, as the outwardly extending end of the magnet frame will serve as a stop for the outward movement of the parts. When the contact finger is made of mag-

netic material it serves to increase the contact pressure in the attracted position of the relay and such increased pressure may be desirable in some cases.

Although a particular embodiment of this invention has been described, it will be understood that various modifications may be made without departing from the scope of the invention.

I claim:

1. A relay comprising a coil, a magnet frame in the form of a flat strip extending along one side and one end of the coil, an armature in the form of a flat strip extending over the coil and bent to extend over the outside of said magnet frame strip and pivotally mounted on the end thereof, a contact finger extending over and engaging both portions of said armature, a compression spring for forcing portions of said finger and armature toward said magnet frame strip, and a fixed contact adapted to be engaged by said contact finger. 10

2. A relay comprising a coil, a magnet frame in the form of a flat strip extending along one side and one end of the coil, an armature in the form of a flat strip extending over the coil and bent to extend over the outside of said magnet frame strip and pivotally mounted on the end thereof, a contact finger extending over and engaging both portions of said armature, a pin fixed to said magnet frame strip and extending outwardly freely through said contact finger and through said portion of the armature strip extending over the magnet frame strip, a compression spring mounted on said pin and restrained at the outer end thereof and exerting pressure against portions of said contact finger and armature toward said magnet frame strip, and a fixed contact adapted to be engaged by said contact finger. 20

3. A relay comprising a coil, a magnet frame in the form of a flat strip extending along one side and one end of the coil, an armature in the form of a flat strip extending over the coil and bent to extend over the outside of said magnet frame strip and pivotally mounted on the end thereof, a contact finger extending over and engaging both portions of said armature, a pin fixed to said magnet frame strip and extending outwardly freely through said contact finger and through said portion of the armature strip extending over the magnet frame strip, a compression spring mounted on said pin and restrained at the outer end thereof and exerting pressure against portions of said contact finger and armature toward said magnet frame strip, a fixed contact adapted to be engaged by said contact finger and means for limiting sidewise movement of the contact finger and armature. 40

4. A relay comprising a coil, a magnet frame in the form of a flat strip extending along one side and one end of the coil, an armature in the form of a flat strip extending over the coil and bent to extend over the outside of said magnet frame strip and pivotally mounted on the end 60

thereof, a contact finger extending over and engaging both portions of said armature, a compression spring for forcing portions of said finger and armature toward said magnet frame strip, said contact finger having guiding extensions embracing the edges of said armature and magnet frame strip, and said armature having guiding extensions embracing the edges of the contact strip, and a fixed contact adapted to be engaged by said contact finger. 5

5. A relay comprising a coil, a magnet frame in the form of a flat strip extending along one side and one end of the coil, an armature in the form of a flat strip extending over the coil and bent to extend over the outside of said magnet frame strip and pivotally mounted on the end thereof, a contact finger extending over and engaging both portions of said armature, said armature portion extending over the outside of the magnet frame strip having a projection for forming a pivot for the contact finger, a compression spring for forcing portions of said contact finger and armature toward said magnet frame strip, and a fixed contact adapted to be engaged by said contact finger. 15

6. A relay comprising a coil, a magnet frame in the form of a flat strip extending outwardly along one side and one end of the coil, an armature in the form of a flat strip extending over the coil and bent to extend inwardly over the outside of said magnet frame strip and pivotally mounted on the end thereof, a contact finger extending over and engaging both portions of said armature, said inwardly extending portion of said armature having a projection for forming a pivot for the contact finger, a compression spring for forcing portions of said contact finger and armature toward said magnet frame strip, said spring being positioned to exert its force on a portion of said contact finger extending between said projection and the inner end of said armature strip, and a fixed contact adapted to be engaged by said contact finger. 20

7. A relay comprising a coil, a magnet frame in the form of a flat strip extending along one side and one end of the coil, an armature in the form of a flat strip extending over the coil and bent to extend over the outside of said magnet frame strip and pivotally mounted on the end thereof, a contact finger extending over and engaging both portions of said armature, a pin fixed to said magnet frame strip and extending outwardly freely through said contact finger and through said portion of the armature strip extending over the magnet frame strip, a compression spring mounted on said pin and restrained at the outer end thereof and exerting pressure against portions of said contact finger and armature toward said magnet frame strip, a fixed contact adapted to be engaged by said contact finger, and a sleeve surrounding said pin for limiting sidewise movement of the contact finger and armature. 30
